J. D. GIBBS

CASING ELEVATOR

Filed Dec. 2, 1921

UNITED STATES PATENT OFFICE.

JAMES D. GIBBS, OF LOUISVILLE, KENTUCKY.

CASING ELEVATOR.

Application filed December 2, 1921. Serial No. 519,452.

To all whom it may concern:

Be it known that I, JAMES D. GIBBS, a citizen of the United States, and resident of Louisville, Kentucky, have invented certain new and useful Improvements in Casing Elevators, of which the following is a specification.

My present invention relates to improvements in what are known as casing elevators, or devices for lifting the casing tubes or pipes used in connection with the drilling of oil wells.

The invention aims to provide a simple, economical, and durable form of apparatus which may be inserted in and rigidly connected to the pipe in an expeditious manner to enable it to be lifted and which may be readily detached therefrom and the invention includes the novel features of construction and arrangement and combination of parts hereinafter described and particularly defined by the appended claims.

An embodiment of my invention is illustrated in the accompanying drawings in which—

Figure 1 is a central vertical section through my improved lifting device.

Fig. 2 is a section on line 2—2 of Fig. 1 on a larger scale; and

Fig. 3, 4 and 5 are views of details.

Referring by reference characters to this drawing, the numeral 1 indicates the main body or carrier portion of the device which has a cylindrical portion which is encircled by the swiveled bearing 2 which is held in place by a screw cap member 3 engaging a correspondingly threaded portion of the body member 1. The member 2 has projecting bosses or trunnions 2^a to which the arms 40 of the lifting bale 4 are pivotally connected. Preferably the upper portion of the body 1 is provided with a shoulder 1^a upon which is seated a washer 5 against which the lower face of the member 2 bears. The body member is provided at its lower end with a head 1^b which is designed to support the radially movable hangers or carrying members 6 which support the slip grip wedges 17 hereinafter more particularly described.

The carrier members or hangers 6, of which there are preferably four as shown in Fig. 2, are provided with inclined inner faces which form a four-sided converging recess in which works an expanding wedge 7 of corresponding shape in cross section

which has an upwardly extending shank 7^a guided in a tubular vertical passage in the head and body 1.

The shank 7^a has a transverse recess 7^b through which passes a key 8^x which slidably engages transverse key-ways formed in the portion of the body or carrier member lying just above the head 1^b, such key-way being indicated at 1^c. This portion of the body or carrier member 2 is provided with external threads and encircled by the internally threaded hub of a hand wheel 8 which has an annular internal recess 8^a formed by a removable flanged portion 8^b into which recess the ends of the key project. By this construction rotation of the hand wheel will cause its hub to screw down or up on the threaded portion and hence through its engagement with the key 8^x to force the wedge 7 downwardly to expand 75 the hanger arms or upwardly to allow them to contract.

The preferred manner of support of the hanger arms is clearly shown in Fig. 1 in which the head is provided with an annular internal recess 1^e and the hanger arms are provided with annularly inturned upper ends 6^e which engage this recess, the upper faces of the hanger arms being rounded, as shown, to permit a rocking movement under 85 the action of the wedge. I prefer to provide for a radially sliding movement to the upper ends of the hanger members in addition to a limited amount of rocking movement and to this end provide springs 9 which are seated in recesses in the radially projecting portions of the hangers and which bear at their inner ends against the bottoms of such recesses and at their other ends against removable screw plugs 1^f.

The lower ends of the hanger member 6 are retained in position by a cap member 10 which has a recessed upper face providing a ring shaped part or flange 10^x within which the lower ends of the hanger members 6 loosely lie, the cap being retained in position by pins 10^a carried by screw plugs 10^b and engaging corresponding recesses in the lower ends of the hanger members. Such recesses are countersunk and the pins are encircled by springs 11 which tend to force the lower ends of the hanger members towards each other. The outer faces of the lower portions of the hanger members are provided with inclined portions preferably of step forma-

tion against which lie the corresponding inclined step faces of the slip wedge members 17. The slip wedges have lugs 17^a which project into grooves 17^b in the lower-most inclined faces of the hanger members and guide pins 17^c pass through openings in these lugs and enter recesses in the hanger members and serve to retain the slip wedges in position and guide them in their vertical movement. The pins at their lower ends are supported by threaded heads 10^d screwed into threaded countersunk recesses in the hanger members and are encircled by helical springs which tend to normally press 10 the slip wedges upwardly.

From the foregoing description it is believed that the operation of my improved lifting device will be readily apparent but it may be briefly stated as follows:

20 When a casing or tube is to be lifted the lower portion of the device, including the slip wedges and hanger arms, is inserted into the tube until the upper end of the tube, or the coupling thereof, reaches or rests in 25 the annular space 1¹, whereupon the hand wheel is rotated to force the wedge 7 downwardly to separate or spread the hanger arms until the slip wedges engage the inner surfaces of the pipe. Lifting power being 30 now applied to the bail, 4, the corresponding movement is imparted to the pipe and if the frictional engagement, due to the expansion of the wedge, is not sufficient or if there is any tendency for slippage, this will take 35 place between the wedges and the hanger members due to their inclined or wedge bearing thereon and such slippage will force the wedges outwardly into tighter engagement with the inner surface of the pipe.

40 Preferably the slip wedges are provided with upwardly inclined gripping teeth as shown.

45 Under ordinary circumstances the reverse movement of the wedge 7 will permit the device to be readily disengaged from the pipe, but to enable the device to be conveniently jarred to loosen it in case it should stick I preferably provide the clamping member 3 with an upwardly extending sleeve 3^a in which is slidably mounted a tubular hammer member 14 provided with a handle 14^a by which it may be raised and forced 50 downwardly to impart a blow to the upper end of the member 1.

55 The hammer or striker 14 is also designed to be pulled out to any necessary distance in order to balance the two ends of the device on its pivotal connection when the pipe is laid down or picked up from a horizontal 60 position.

Having thus described my invention, what I claim is:

65 1. In a device of the class described, a carrier member, radially movable members supported thereby, means for moving said

members, and gripping wedges slidably carried by said radially movable members.

2. In a device of the class described, a carrier member, radially movable members connected therewith having inclined stepped faces, gripping members supported by said radially movable members and having co-acting inclined stepped faces slidably engaging said stepped faces, and means for moving said radially movable members. 75

3. In a device of the class described, a carrier member, radially movable members connected therewith having stepped inclined faces, gripping members supported by said radially movable members and having co-acting inclined faces slidably engaging said stepped faces, and spring means for pressing said gripping members in one direction. 80

4. In a device of the class described, a carrier member, a plurality of radially movable hangers depending therefrom, having inclined stepped faces, spring pressed gripper members having correspondingly inclined faces slidably engaging the inclined faces of said hangers, and wedge means for imparting radial movement to the hangers. 85

5. In combination, a carrier member having a tubular passage and a head provided with an annular recess, a plurality of hangers having inclined inner faces and having outwardly extending flanges at their upper ends engaging said annular recess, gripper devices carried by said hangers, an expanding wedge cooperating with the inclined faces of the hangers and having a shank located in said tubular recess, and means for imparting vertical movement to said shank. 95

6. In combination, a carrier member having a tubular passage and a head provided with an annular recess, a plurality of hangers having inclined inner faces and having outwardly extending flanges at their upper ends engaging said annular recess, springs interposed between the said flanges and the wall of the recess, gripper devices carried by said hangers, an expanding wedge cooperating with the inclined faces of the hangers and having a shank located in said tubular recess, and means for imparting vertical movement to said shank. 100

7. In combination, a carrier member having a hollow part provided with a depending head, radially movable hangers carried by said head carrying pipe gripping means, wedge means for moving said hangers having a shank extending into said hollow part, said shank having a key passage and said hollow part a screw threaded exterior and transverse keyways aligning with said key passage, a nut threaded on said screw threaded exterior, and having an annular internal groove and a key located in said key passage and keyways and having its ends seated in said groove. 110

8. In combination, a carrier member, a 115

130

collar fast thereon having trunnions, a bail pivotally connected with said trunnions, a nut threaded on the upper end of the carrier member for clamping said collar and 5 having a tubular extension, radially movable hangers supported by said carrier member, and carrying pipe gripping means, wedge means for operating said hangers, and an impact device slidably carried by 10 said tubular extension for jarring the gripping means loose from the pipe.

9. In combination, a carrier member, pipe gripping means supported thereby, wedge means for operating said gripping means, 15 and an impact device slidably carried by said carrier member.

10. In combination, a carrier member, a plurality of annularly arranged hangers loosely supported therefrom and having inclined inner faces, a wedge cooperating with 20 said inner faces with means for operating the same, an element having a ring shaped part encircling the lower ends of said hangers, pins carried by said ring shaped part 25 slidably engaging recesses in said hangers, said hangers having inclined outer faces, gripper devices having inclined faces slidably held to the faces of the hangers, and

springs interposed between said grippers and said ring shaped part. 30

11. In combination, a carrier member, a plurality of annularly arranged hangers loosely supported therefrom and having inclined inner faces, a wedge cooperating with 35 said inner faces with means for operating the same, an element having a ring shaped part encircling the lower ends of said hangers, pins carried by said ring shaped part slidably engaging recesses in said hangers, 40 said hangers having inclined stepped outer faces, gripper blocks having correspondingly stepped inclined faces, said hangers having vertical grooves and said blocks having lugs engaging said grooves, guide pins passing through openings in the lugs and 45 held to the hangers, a ring shaped part encircling the lower ends of the hangers and with which they are yieldably connected, and springs encircling the guide pins between the lugs and said ring shaped part. 50

In testimony whereof I affix my signature.

JAMES D. GIBBS.
